COMBINATION CONTROL

Homer E. Malone, Milwaukee, Wis., assignor to
 Perfex Corporation, Milwaukee, Wis., a corporation of Wisconsin

Application June 4, 1942, Serial No. 445,740

2 Claims. (Cl. 137—69)

1

This invention relates in general to automatic combination controls and is more particularly concerned with the control of gas burners.

In many types of domestic gas burners now in use, a damper is provided for the control of secondary air to the burner. It is desirable to have this damper open only while the burner is in actual operation. When the burner is shut off it is desirable to close the air damper to prevent flow of air through the furnace, for such air flow would cool the furnace and cause wasting of heat up the furnace stack. In order to operate the secondary air damper it has been usual to provide a lever arm on the gas valve, this lever being shifted when the valve opens or closes for thereby opening or closing the damper. The presence of such a lever on the gas valve raises the problem of preventing actuation of the valve by manual manipulation of the lever. If the lever is capable of opening the valve, there is danger of the valve being manually opened at times when it is dangerous for the valve to open. For example, there is a possibility of the valve being opened when the furnace is overheated, or when the pilot is out. In order to prevent any possibility of danger from this source, it has been proposed to arrange the damper lever so that manual operation thereof is incapable of moving the valve. In the past this has required fairly complicated driving arrangements or strain releases.

It is the primary object of the present invention to provide an arrangement by which a single motor operates both a valve and lever, and in which the lever is incapable of changing the position of the valve.

It is a further object of the invention to provide a combination control in which a single motor operates two control devices, one control being operated by the motor through a cam mechanism which renders this control member incapable of changing the motor position or the position of the other control member.

Other objects of the invention will become apparent from the following description and the appended claims.

For a full disclosure of the invention, reference is made to the following detailed description and the accompanying drawings.

Referring to the drawings,

Fig. 1 is a side view partly in section of a gas valve and lever mechanism;

Fig. 2 is a sectional view taken at right angles to Fig. 1;

2

Fig. 3 is a sectional view taken on line 3—3 of Fig. 1;

Fig. 4 is a view similar to Fig. 2, but showing a slight modification;

Fig. 5 shows the application of the valve and lever mechanism to a secondary air damper which opens inwardly; and

Fig. 6 shows the application of the valve and lever mechanism to a secondary air damper which opens outwardly.

Referring to the drawings, reference character 1 indicates generally a valve body formed with a transverse partition 2 containing a valve port 3 for placing inlet and outlet chambers 4 and 5 in communication. The upper portion of the valve body is formed bell-shaped, having a circular flange portion 6. Secured to the flange 6 is an inverted cup-shaped housing member 7, this member having a circular flange 8. The housing member 7 is secured to the flange 6 by means of screws 9, a diaphragm 10 being interposed between the flanges 6 and 8. The housing member 7 is formed with a central opening 11. Extending across this opening is a flat cross member 12, this cross member being secured to the member 7 by means of screws 13. These screws also secure a pair of upstanding bracket members 14 and 15 to the upper face of the housing member 7. The cross member 12 is formed with a central opening through which the end of a hollow stem 16 extends. This stem is provided with a shoulder engaging the lower side of member 12 and is held in place by a nut 17. As shown in Fig. 4, the hollow stem 16 extends downwardly and has its lower end secured in a fluidtight manner to a bellows head 18. This bellows head is in turn secured to the lower end of a bellows 19. The upper end of this bellows is secured to an annular member 20 which is in turn secured to a cup-shaped clamping plate 22 which slides on stem 16. The member 20 is also sealed to a cup-shaped bellows housing member 23 which surrounds the bellows 19. This housing member is formed with a flange 24 at its upper end which cooperates with the clamping plate 22 to clamp the sealing diaphragm 10 therebetween. A spring 25 is located inside the bellows 19, the lower end of this spring engaging the bellows head 18 (Fig. 4) and the upper end of this spring engaging the clamping plate 22 and urging it upwardly.

Extending upwardly from the stationary hollow stem 16 is a tube 27, the upper end of which is secured to a generator 28. This generator is cylindrical in shape and has an elec-

tric heating element 29 wrapped around its lower end. This heating element has its leads connected to suitable terminals 30 and 31 which are carried by an upstanding terminal plate 32 of insulating material. The interior of the generator 28, the tube 27, stem 16 and the space 33 between the bellows 19 and the cup member 23 are filled with a suitable volatile fluid, such as alcohol. This filling is accomplished through a downwardly extending filling stem 34 (Figs. 2 and 4), the end of which is pinched and soldered after the filling operation. When the electric heater is not energized, no pressure is generated in the generator 28, and the spring 25 causes the bellows to be expanded. Inasmuch as the bellows head 18 is stationary, it will be apparent that the spring 25 in expanding the bellows 19 will force the upper or movable end of the bellows upwardly, thus causing the cup member 23 to be in the raised position shown in the drawings. When the electric heater 29 is energized, however, vapor will be formed in the generator which drives the liquid out of the generator through the tube 27 and the stem 16 into the space 33 between the bellows and cup member. This forces the cup member downwardly against the action of spring 25, this being permitted by collapsing of the bellows 19. During this movement, the clamping plate 22 in cooperation with the stem 16 serves to guide the upper end of the bellows. When the electric heater is deenergized, the generator will cool, thereby condensing the vapor therein. This will permit the spring 25 to force the cup member 23 upwardly, thus driving the liquid from the space 33 back into the generator. Thus the cup member 23, together with all of the parts attached thereto, rises when the electric heater is deenergized and lowers when the electric heater is energized.

The heat motor construction above described is claimed in my copending application Serial No. 341,721, filed June 21, 1940. For a more detailed description of the construction and operation of the heat motor, reference is made to said copending application.

The lower end of the cup member 23 is attached to a hollow sleeve 36 which surrounds the filler tube 34. The lower end of the sleeve 36 is of reduced diameter as at 37 and fits into a guide member 38. The guide member 38 is secured to a valve member 39 cooperating with the valve port 3. The guide member 38 also fits into a hollow boss 40 formed in a plug 41 which closes the bottom of the valve body. A spring 42 is interposed between the plug 41 and valve member 39 for urging this valve member upwardly against its seat. It should now be apparent that when the cup member 23 is forced downwardly by energization of the electric heater, the shoulder 43 on member 36 engages the guide member 38, which forces the valve member 39 downwardly against the action of spring 42, thereby opening the valve. When the electric heater is deenergized the cup member 23 rises under the combined action of springs 25 and 42, the spring 42 serving to hold the valve member against its seat when the cup member 23 reaches its upper position.

The generator 28 is surrounded by an annular member 45 preferably of heat insulating material which is supported on spacers 46 and 47 engaging the housing member 7, screws 48 extending through these spacers and being screw-threaded into the cap 7. The screws 48 also se-

cure a U-shaped bracket 50 to the top of member 45. A cylindrical cover 51 for the generator is held in place by a screw 52 which is received in the bracket 50.

Referring now to the damper operating mechanism, this mechanism consists of a secondary air lever 53 which extends through slots 54 and 55 in the cover 51. As shown in Fig. 3, this lever is of two-part construction, being formed of bent strips 56 and 57 which are riveted together. These strips lie parallel and adjacent each other outside of the cover. However, within the cover these strips diverge to form a yoke. These strips are pivoted to a pivot pin 58 which is supported by the bracket members 14 and 15. This pin is formed with an enlarged intermediate portion 59 which acts as a spacer. The strips 56 and 57 are provided with downwardly extending portions 60 and 61. A pin 62 extends through the downward extensions 60 and 61, this pin being formed with a suitable spacer portion or cam follower 63 located between the extensions. The pin 62 also extends through arcuate slots 65 formed in bracket members 14 and 15. This arrangement serves to limit movement of the lever 53 about its pivot.

The cam follower 63 cooperates with cam members 66 and 67. These cam members are preferably formed as legs of a U-shaped bracket member which is secured to the clamping plate 22. Suitable openings are provided in the plate 12 through which the cam members or legs 66 and 67 extend. As shown in Fig. 2, the cam members are each provided with an inclined cam surface 70, this inclined surface being intermediate high and low cam surfaces 71 and 72, both of which lie in planes parallel with the path of movement of the longitudinal cam members. The cam members 66 and 67 are preferably guided in their longitudinal movement by means of a guide pin 73 which extends between the brackets 14 and 15.

Referring to Fig. 5, this figure shows the application of the valve to a burner having a secondary air damper which opens inwardly. For an application of this type a weight 75 is attached to the left hand end of the lever arm 53. The right hand end of this arm is connected by a chain 76 to the secondary air damper 77. The weight 75 is made sufficiently heavy to hold the damper 77 in closed position. If the valve is applied to a burner having a secondary air damper which opens outwardly, the arrangement shown in Fig. 6 is preferably employed. For an application of this type, a chain 78 is attached to the damper 79, this chain running over a pulley 80 and being attached to the right hand end of the lever 53. Thus in both arrangements the lever 53 is biased counter-clockwise by an external force and serves to open the damper upon clockwise rotation of the lever about its pivot.

When the heat motor is deenergized, the valve assumes closed position as shown. Also the cam follower pin 63 engages the low surface 72 on the cam, thus permitting the lever 53 to assume its counter-clockwise position in which the secondary air damper is closed. When the parts are in the positions shown it should be noted that the secondary air lever 53 is incapable of causing any opening movement of the valve. Thus if the lever 53 is manually rotated clockwise, the cam follower pin 63 merely becomes disengaged from the cam surface 72 and the valve remains stationary. It should also be noted that when the

parts are in this position the lever 53 cannot affect the valve position, even if the lever is forced in a counter-clockwise direction. Thus at this time the cam follower 63 will merely be forced against the cam members, urging them against the guide pin 73. This applies no longitudinal force whatever to the cam members and consequently does not affect the valve position.

When the heat motor is energized, the entire bellows assembly moves downwardly, as previously described, for moving the valve member 39 away from its seat. With the arrangement shown in Fig. 2, the shoulder 43 will engage the guide 38 for the valve member before the inclined cam surface 70 engages the cam follower 63. Thus with this arrangement the valve opens and the secondary air damper remains stationary during initial opening movement of the valve. When the valve approaches wide open position, the inclined surface 71 engages the cam follower 63, thereby urging the lever 53 clockwise about its pivot for opening the secondary air damper. When the valve reaches wide open position, the raised cam surface 71 engages the cam follower 63. At this time it should be noted the secondary air damper is positively held in open position and cannot be closed manually. Thus if an attempt is made to rotate lever 53 counter-clockwise, the cam follower merely is forced against the cam surface 71. Inasmuch as this surface is parallel with the direction of movement of the cam, the lateral force applied to the cam by the follower produces no longitudinal component of force. At this time the guide pin 73 restrains lateral motion of the cams and prevents any injury to the bellows assembly. Thus regardless of the force applied to the secondary air lever 53, the valve will remain in open position and no harm can result.

In controlling certain types of burners, it is desirable to have the secondary air damper open before gas is admitted to the burner. This result can be obtained simply by changing the relation between the cam surfaces and changing the position of the shoulder 43 on the valve stem. In Fig. 4 it will be noted that when the valve is in closed position the inclined surface 70 engages the cam follower 63 and that a considerable space is present between the shoulder 43 on the valve stem and the valve guide 38. Thus when the heat motor is energized, causing downward motion of the bellows assembly and cams, the secondary air lever is rocked clockwise upon initial movement of the parts. At this time the valve member 39 remains stationary due to the fact that the shoulder 43 has not yet engaged the guide 38. After the lever arm 53 has been rocked to open the secondary air damper, the shoulder 53 engages the guide 38. Thus upon continued downward movement of the bellows assembly, the valve member 39 is urged downwardly for permitting flow of gas to the burner.

From the foregoing description it should be apparent that the present invention provides a very simple construction for actuating the secondary air damper of a gas valve, this arrangement serving to prevent operation of the valve by manipulation of the lever arm for the damp-

er. It should also be apparent that the present invention prevents any possibility of injury to the various parts of the valve mechanism due to misuse of the secondary air lever. While the invention is of particular utility in controlling gas burners, it is not limited to this particular application. As many modifications and adaptations may be made without departing from the scope of the invention, it is desired to be limited only by the appended claims.

What is claimed is:

1. A combination gas valve and damper operator for a gas fired furnace having a gas burner and a secondary air damper, comprising, a valve casing having a valve port therein, a valve member cooperating with said valve port, a valve stem for actuating said valve member, a motor for shifting said valve stem longitudinally for opening and closing the valve, a cover for covering at least a portion of said motor, a lever extending from said cover in a direction substantially perpendicular to said valve stem, a longitudinal cam within said cover and actuated by said motor in a direction parallel with said valve stem, a cam follower cooperating with said lever and cam to cause movement of said lever upon movement of the valve, said cam having an inclined surface adapted to engage the cam follower as the valve stem is shifted between open and closed positions, the cam also having a surface substantially parallel with the direction of movement of the cam, said last mentioned surface engaging the follower when the valve is at one of said positions whereby the valve cannot be moved toward the other of said positions by manual actuation of said lever.
2. A combination gas valve and damper operator for a gas fired furnace having a gas burner and a secondary air damper, comprising, a valve casing having a valve port therein, a valve member cooperating with said valve port, a valve stem for actuating said valve member, a motor for shifting said valve stem longitudinally for opening and closing the valve, a cover for covering at least a portion of said motor, a lever extending from said cover in a direction substantially perpendicular to said valve stem, a longitudinal cam within said cover and actuated by said motor in a direction parallel with said valve stem, and a cam follower cooperating with said lever and cam to cause movement of said lever upon movement of the valve, said cam having an inclined surface adapted to engage the cam follower as the valve stem is shifted between open and closed positions.
